Thurston & Dales.

UNITED STATES PATENT OFFICE.

HENRY W. AVERY, OF CLEVELAND, OHIO, ASSIGNOR TO THE AVERY STAMPING COMPANY, OF SAME PLACE.

SEAT FOR HARVESTERS OR THE LIKE.

SPECIFICATION forming part of Letters Patent No. 683,675, dated October 1, 1901.

Application filed May 8, 1901. Serial No. 59,204. (No model.)

whom it may concern:

Be it known that I, HENRY W. AVERY, a citizen of the United States, residing at Cleveland, in the county of Cuyahoga and State of Ohio, have invented a certain new and useful Improvement in Seats for Harvesters or the Like, (Case A,) of which the following is a full, clear, and exact description, reference being had to the accompanying drawings.

10 This invention relates to pressed-steel seats such as are used on harvesters, cultivators, hay-rakes, and various agricultural machines.

15 Its object is to provide a seat which while being simple in construction shall have the metal disposed where it is most needed, so that an equally strong seat may be made from less material, thereby reducing the cost.

20 These seats are commonly supported centrally on a suitable spring-bar, and the tendency to break comes at the center portion adjacent to the support. To strengthen the seat at this point, it has been customary to corrugate it; but as in stamping sheets of sheet metal it is impracticable to have the 25 original sheet thicker at one point than another the whole seat has been made heavier than is necessary, so as to have the right thickness for this center portion. The present invention is designed to overcome this,

30 providing a simple and efficient reinforcing-plate at the center, which shall so strengthen the seat at this point that the total weight of the seat and the reinforcing may be less than the corrugated seat alone. In applying this

35 reinforcing I employ the same rivets to hold it to the seat and to form stops for the supporting-bar. No extra rivets beyond those necessary to define the position of the supporting-bar are employed to hold the rein-

40 forcing in place, or, stated conversely, no extra rivets beyond those necessary to hold the reinforcing in place are necessary to define the supporting-bar. This conjoint double action of the rivets is what allows the seat to 45 be produced with the necessary cheapness, and it is an essential element of my invention.

The drawings clearly disclose the invention.

Figure 1 is a bottom plan of the seat and its supporting-spring. Fig. 2 is a vertical section thereof on the line 2 2 of Fig. 1, and Fig. 3 is a fragmentary cross-section on the line 3 3 of Fig. 1.

Referring to the parts by letters, A represents the seat proper, which is stamped from 55 a single piece of sheet metal and is lightened by suitable openings, as a. The central portion a' of this seat is flat, and directly beneath this portion is the reinforcing-plate B, which is preferably circular, as shown. This 60 reinforce is secured to the seat by the rivets C, of which there are preferably four. These rivets securely hold the reinforcing to the seat, while their downwardly-projecting heads form stops limiting the supporting-bar D. 65 There being four rivets employed at the four corners at an imaginary square, the bar D may extend either in the direction shown in the drawings or at right angles thereto and be defined in position in either event. The bar 70 is held in place by the bolt E taking through the seat proper, the reinforcing, and the bar and clamped with a nut e.

The seat proper may be made of very light sheet material, and the reinforcing of other 75 sheet material of the proper thickness, so that the total weight is disposed where it is most efficient. The rivets C being nearly flat on the top are not objectionable to the rider, and they are very easily applied. 80

I claim—

1. A seat made of sheet metal and reinforced by a plate held to the seat by rivets which have downwardly-projecting heads adapted to abut a supporting-bar, substantially as described. 85

2. A seat made of sheet metal and reinforced by a plate held to the seat by a plurality of rivets, which rivets have downwardly-extending heads and are adapted to have 90 their inner sides engage the edges of a supporting-bar beneath the seat, substantially as described.

3. The combination of a sheet-metal seat

proper having a flat central portion, a flat reinforcing-plate directly beneath said central portion, and rivets projecting through the reinforcing-plate and the seat and having 5 substantially flat heads above, and projecting heads below whereby said rivets may serve the double purpose of holding the reinforcing-plate to the seat and providing

stops for a supporting-bar abutting their inner sides, substantially as described.

In testimony whereof I hereunto affix my signature in the presence of two witnesses.

HENRY W. AVERY.

Witnesses:

ALBERT H. BATES,
H. M. WISE.

DISCLAIMER.

683,675.—*Henry W. Avery*, Cleveland, Ohio. SEAT FOR HARVESTERS OR THE LIKE.

Patent dated October 1, 1901. Disclaimer filed June 30, 1902, by the patentee and the assignee, *The Avery Stamping Company*:

Enter their disclaimer—

“To the construction which is defined by claims 1 and 2 of said patent in the following words, to wit:

“1. A seat made of sheet metal and reinforced by a plate held to the seat by rivets which have downwardly-projecting heads adapted to abut a supporting-bar, substantially as described.

“2. A seat made of sheet metal and reinforced by a plate held to the seat by a plurality of rivets, which rivets have downwardly-extending heads and are adapted to have their inner sides engage the edges of a supporting-bar beneath the seat, substantially as described.”—(*Official Gazette July 8, 1902.*)
